UNITED STATES PATENT OFFICE.

FLOYD D. STOWE, OF WILMINGTON, DELAWARE, ASSIGNOR TO E. I. DU PONT DE NEMOURS POWDER COMPANY, OF WILMINGTON, DELAWARE, A CORPORATION OF NEW JERSEY.

BUNG-PRESS.

1,274,208.

Specification of Letters Patent. Patented July 30, 1918.

Application filed April 24, 1914. Serial No. 834,084.

To all whom it may concern:

Be it known that I, FLOYD D. STOWE, of Wilmington, in the county of New Castle and in the State of Delaware, have invented a certain new and useful Improvement in Bung-Presses, and do hereby declare that the following is a full, clear, and exact description thereof.

My invention relates particularly to a machine for forming bung-holes and bung-hole closures used on kegs, but has special reference to such a machine as used in connection with steel powder kegs.

The object of my invention is to provide a machine of the above character which will automatically and continuously produce bung-holes in keg heads by punching the holes, raising bosses around the holes to permit the attachment of ears, and which automatically feeds the ears into the machine and fastens the ears on the bosses formed around the bung-holes so that thereby the closures of the keg bung-holes may be readily secured to the ears. Further objects of my invention will appear from a consideration of the detailed description thereof which is set forth herein-after.

While my invention is capable of embodiment in many different forms, for the purpose of illustration I have shown only one form thereof in the accompanying drawings, in which,

Figure 1 is a front elevation of a machine made in accordance with my invention,

Fig. 2 is an end elevation of the same,

Fig. 3 is a vertical section taken through the same,

Fig. 4 is a horizontal section of the same,

Fig. 5 is a vertical section of the ear feeding apparatus enlarged,

Fig. 6 is a plan view of certain details of the ear feeding mechanism,

Fig. 7 is an enlarged plan view of a portion of the feeding band,

Fig. 8 is a transverse section of a portion of the feeding band showing the same while not containing a blank, and

Fig. 9 is a similar cross-section of the band, but showing a band when clamping a blank in place thereon under the influence of the cam plate which is used for holding the blanks in position on the band,

Figs. 10 and 11 are, respectively, a plan

and a central section of a keg-head formed by the machine.

In the drawings I have shown a main frame 1, which has at one end a pair of stationary bearings 2 to receive a shaft 3 and at the other end a pair of adjustable bearings 4 to receive a shaft 5. Each of the adjustable bearings 4 is carried upon slide-ways 5^a located on the main frame 1, the position of the bearings 4 being determined by screws 6 passing from the main frame to a point adjacent to the sides of the sliding bearings 4. The shafts 3 and 5 carry respectively drums 7 and 8 to receive a flexible band 9 of metal or any other suitable material. At intervals along this band 9 there are circular openings 10 to receive the blanks to be operated upon. Between these openings 10 strengthening strips 11 are riveted to the face of the band 9. In order to secure blanks 12 in place in the openings 10, each opening 10 has adjacent thereto on the band, a pair of tapered catches 13 at one side of the openings 10, and a pivoted catch 14 at the other side thereof. Each of the catches 14 is pivotally supported in a pair of brackets 15 connected to the face of the band 9 by bolts 16, said pair of brackets 15 being constructed to receive springs 17 to normally force the catches 14 outwardly in the position shown in Fig. 8. Blanks are placed in the openings 10 by hand when the openings reach the position immediately above the drum 8. As the band now advances the blanks will be clamped in position automatically as soon as the catches 14 reach the position of a cam plate 18, which is located at the front of the machine at one side of the band 9. It will be noted that the cam plate 18 has at its extreme left end an inclined surface 19 to permit the catches 14 to be gradually closed. Said cam plate 18 is also supported for a certain degree of yielding movement by being attached to the main frame 1 by screws 20 which are loosely supported in sockets 21 in said frame, and by the fact that the side of the cam plate 18 is also supported against the faces of a plurality of spring-pressed plungers 22 supported in sockets 23 in the main frame 1. The band 9 is given an intermittent movement in the following manner. The shaft 3 has a ratchet 24 which is moved at intervals by a

pawl 25 carried upon a pair of oscillating arms 26 loosely carried by the shaft 3 on the opposite sides of the ratchet 24. The pawl 25 is thus supported between the oscillating arms 26 and bears upon the periphery of the ratchet 24. A link 27 connects the oscillating arms 26 with a lever 28 pivoted to the main frame near its center and having a roller 29 at the other end thereof which 5 coöperates with a cam 30 secured to a counter-shaft 31, which is supported in bearings 32 upon the main frame of the machine. This counter-shaft 31 carries a gear 32^a which is driven from a main driving shaft 33 having a pulley 34, which shaft is supported in bearings 35 also on the main frame of the machine. The application of power is controlled by a foot treadle 35^a connected by a link 36 with a lever 37 which 10 controls a clutch 38 through a link 39. Near the center of the machine the counter-shaft 31 has an eccentric 40 which is connected by journal bearings 41 with a sliding carriage 42. This sliding carriage 42 has 15 vertical slides 43 at the two sides thereof, the vertical slide 43 at the right of Fig. 1 contacting with a fixed removable guide 44 secured to the main frame by screws 45, while the left vertical slide 43 coöperates 20 with an adjustable guide 46, the position of which is determined by adjusting screws 47 and fastening screws 48 for securing the slide in the adjusted position. Two operations are carried out by one reciprocation 25 of the sliding carriage 42, said sliding carriage carrying devices which operate upon two blanks located in the flexible band 9 at the same time. The first of these operations is effected by the apparatus at the 30 left of the sliding carriage 42 which comprises a punch 49 supported on a subsidiary sliding carriage 50 and adapted to be adjusted by the adjustment of said sliding carriage. In order to adjust the sliding carriage 45 the latter is provided at its upper end with a screw-thread 51 to which are attached a pair of movable collars 52 located above and below a portion of the main sliding carriage 42. This punch 49 is so formed that 50 it coöperates with a die 53 situated below the band 9 to punch out a hole in the blank for forming the bung-hole of the keg and at the same time raises a boss around the head thus punched out. The blank thus 55 provided with a bung-hole and boss around the hole is then ready for the next succeeding operation, that is to say, the application to the bung-hole of an ear 53^a and riveting or fastening the same to the bung-hole. 60 This is carried out by the apparatus at the right of the sliding carriage 42. This apparatus is so constructed, however, as not to operate except when a blank is at the same time in the opening immediately below the 65 punch 49, so that by this means the apparatus for feeding in an ear 53^a and attaching the same to the head around the bung-hole will only be caused to operate when there has been a blank inserted in the band 9 and previously operated upon to provide a bung-hole and boss around the bung-hole. In order to accomplish this result a vertical sliding rod 54 is adapted to contact with a blank when in the opening in the band immediately below the punch 49. A spring 55 70 upon the rod 54 normally moves the rod 54 downwardly so as to also move downwardly a catch or arm 56 pivoted to the sliding carriage 42 and supported upon the upper end of the rod 54. When there is a blank in 75 the opening 10 immediately below the punch 49, the rod 54 will contact therewith so that upon the downward movement of the sliding carriage 42 the rod 54 and the arm 56 supported by the same will be moved upwardly, thus bringing the end of the arm 56 into a position such as to move a horizontal sliding rod 57 to the right of the machine as shown in Fig. 1. This rod 57 is supported in brackets 58 attached to the 80 sliding carriage 42; and a spring 59, which is attached to one of the brackets 58, and which engages a catch 60 upon the top of the sliding rod 57, normally moves said rod toward the left of the machine. When the 85 rod 57 has been thus moved to the left of the machine this end will not extend beyond the right-hand bracket 58 and said rod will, therefore, not make any connection with the parts with which it is adapted to coöperate. 90 When, on the other hand, however, the rod 57 has been moved to the right of Fig. 1, owing to the presence of a blank beneath the punch 49, the end of the rod 57 will extend beyond the bracket 58. In this position of the rod 57 its end will overlie a spring-pressed catch 61 carried on the end of a lever 62 pivoted to the main frame of the machine. This lever 62 is connected at 95 its end by means of a link 63 to a slotted arm 64 on a lever 65 which is also pivoted to the main frame. The lever 65 has in addition to the arm 64 an upwardly directed arm 66 and a laterally directed arm 67. The latter arm 67 is provided for connection by means of a link 68 with a lever 69 extending beneath the band 9 so as to be operated at its other end by a rod or plunger 70, which extends upwardly through the center of a die 71, located below the band 9. 100 Said die 71 coöperates with a punch 72 carried upon a slidable adjustable carriage 73, which has at its upper end a screw-threaded extension 74 arranged for adjustment by means of collars 75 located above and below a portion of the sliding carriage 42, respectively. The upwardly directed arm 66 has a pin 76 which coöperates with a slot 76^a in a lever 76^b pivoted to the main frame. 105 This lever 76^b has at its upper end a pair of 110

slots 76^c which co-act with the ends of a rod 76^d attached to a movable plate 77. The movable plate 77 is supported so as to slide upon an inclined stationary plate 78, said movable plate 77 being connected to the rod 76^d by means of a screw 78^a and spacing plate 78^b, which are situated in a slot 78^c near the upper end of the plate 78. Near its center, the plate 77 has a pair of screws 78^d which pass through a spacing plate 78^e located in a slot 78^f in the body of the plate 78, said screws passing into an angular guide plate 79 having inclined forward surfaces 80, which guide plate 79 slides upon the top 10 of the plate 78. Near its forward end, the plate 77 carries a finger 81, having a notch 81^a similar in shape to a finger-nail upon its upper surface, which finger 81 is connected to the plate 77 by screws 81^b. The notch 81^a is provided to engage with the holes in the centers of the ears as they are fed downwardly into the machine. The upper end of the lever arm 66 is connected by a link 82 with a bar 83 extending across the 20 entire surface of the plate 77, said bar 83 having at each side thereof a longitudinal rod 84 upon the upper surface of which there is a guide plate 85 located over the top of the plate 78. The two rods 84 are connected together at their forward ends by a plate 86 which extends beneath the surface of the plate 77, which plate 86 has at each end thereof a block 87 extending upwardly and along the side of the rod 84, 30 which is adjacent thereto. Sheet metal fingers 88 are interposed between the ends of the rods 84 and the blocks 87, and screws 89 pass through the blocks 87 and into the rods 84 so as to secure the said rods 84 and fingers 88 to the plate 86. Above the plate 78 there is provided a hopper 91 fed from chute 90, which hopper is supported upon the main frame in any suitable manner. The hopper 91 is formed with a forward extension 92 above the plate 78 to limit the downward movement of the ears from the hopper 91, and at the front of the extension 92 and on top thereof, there is a spring catch 93 which is riveted to the extension 92 40 at its upper end and which has a recess 94 at its lower end to receive the bent end of the ear 53^a which is to be applied to the bung-hole of the keg head.

In the operation of my invention, heads 55 are placed in the openings 10 in the band 9 as said openings are brought above the top of the drum 8 in the intermittent movement of the band, which intermittent movement is effected by the ratchet 24, the pawl 25 and 60 the cam 30 with connecting parts. As the band 9 passes forwardly, the catches 14 thereon come into contact with the plate 18, thereby clamping the blanks securely in position in the openings 10. When a blank 65 comes below the punch 49, the reciprocation of the carriage 42 causes the punch 49 to co-operate with the die 53 to punch out a hole for the bung in the head of the keg, and at the same time raise the boss around the head for the attachment of the ear 53^a. When a 70 keg head has thus been operated upon by the punch 49 and the die 53, the rod 54 will have been operated so as to move the horizontally movable rod 57 beyond the end of the right-hand bracket 58. The rod 57 will 75 then project into the path of the catch 61 and the next downward movement of the carriage 42, which will be the next movement of the carriage 42 taking place after the removal of the keg head from under the punch 80 49 to a position under the punch 72, will operate the lever 62 until the bar 57 has passed beyond the end of the catch 61. In this movement of the lever 62, the two fingers 88 will have been moved by the link 82 so as 85 to push one of the ears 53^a on to the keg head above the bung-hole and around the boss formed upon said keg head and at the same time the finger 81 will have been withdrawn and engaged with the hole in the next succeeding ear 53^a being fed downwardly in the hopper 91, the movement of the finger 81 being accomplished by the lever 76^b. After the lever 62 has ceased moving, the punch 72 co-operates with the die 71 to rivet 90 or fasten the ear 53^a to the keg head by turning over the edges of the boss upon the top of the ear 53^a to permanently fasten the same in place. At the same time, the contacting of the punch 72 with the die 71 will 95 cause the plunger 70 to move downwardly, which movement will bring about a movement of the fingers 88 and the finger 81, exactly the reverse of the movements just described; that is to say, this movement will cause the two fingers 88 to be withdrawn from above the keg head and at the same time the finger 81 will be pushed forwardly 100 so as to force the ear 53^a which it engages to a position in which the folded edge of the ear 53^a springs into the notch 94 in the catch 93. The continued operation of the machine brings about a continuous repetition of these movements, whereby keg heads are provided with bung-holes and 105 bosses around the holes, over which ears are fed upon the bosses around the bung-holes and the ears are riveted or fastened in position by turning over the edges of the bosses on to the top of the ears. The heads, as they 110 are finished in the manner indicated, are carried to the right of the machine by the band 9 where the catches 14 become released from the action of the plate 18, whereupon the heads, with attached ears, fall away from 115 the band so as to be removed for final attachment to the kegs. The ears 53^a are provided to receive slides (not shown) to close the bung-holes.

While I have described my invention above 130

in detail, I wish it to be understood that many changes may be made therein without departing from the spirit of my invention.

I claim—

- 5 1. In a press, means for feeding heads, devices for making bung-holes, and means for producing bosses thereon.
- 10 2. In a press, means for feeding heads, devices for making bung-holes, means for producing bosses thereon and for providing ears on the bosses.
- 15 3. In a press, means for feeding heads and devices for making bung-holes and producing bosses thereon and providing ears on the bosses, comprising a punch and die for forming the bung-holes and a punch and die for fastening the ears thereon.
- 20 4. In a press, means for feeding heads and devices for making bung-holes and producing bosses thereon and providing ears on the bosses, the ear providing means having a feeding means adapted to feed ears only when a head has been inserted in the press.
- 25 5. In a press, means for feeding heads and devices for making bung-holes and producing bosses thereon and providing ears on the bosses, the ear providing means having connections from the bung hole and boss producing devices to cause the feeding of an ear only when a head has first been operated upon by the bung hole and boss producing devices.
- 30 6. In a head press, means for providing ears on bosses comprising a punch and die and means for feeding ears on the heads comprising a hopper for ears, a primary ear-feeding device and a secondary ear-feeding device.
- 35 7. In a head press, means for providing ears on bosses comprising a punch and die and means for feeding ears on the heads comprising a hopper for ears, a primary ear-feeding device, a secondary ear-feeding device, and connections from the punch and die for operating the primary and secondary feeding devices simultaneously in opposite directions.
- 40 8. In a head press, means for providing ears on bosses comprising a punch and die and means for feeding ears on the heads comprising a hopper for ears, a primary ear-feeding device, a secondary ear-feeding device, and connections from the punch and die for operating the primary and secondary feeding devices simultaneously in opposite directions, said connections being adapted to operate the primary feeding device rearwardly and the secondary feeding device forwardly before the die and punch are together.
- 45 9. In a head press, means for providing ears on bosses comprising a punch and die and means for feeding ears on the heads comprising a hopper for ears, a primary ear-feeding device, a secondary ear-feeding device, and connections from the punch and die for operating the primary and secondary feeding devices simultaneously in opposite directions, said connections being adapted to operate the primary feeding device rearwardly and the secondary feeding device forwardly before the die and punch are together and to operate the feeding devices in the opposite direction thereafter.
- 50 10. In a head press, means for providing ears on bosses comprising a punch and die and means for feeding ears on the heads comprising a hopper for ears, a primary ear-feeding device engaging the holes in the ears, and a secondary ear-feeding device engaging the edges of the ears.
- 55 11. In a head press, means for providing ears on bosses comprising a punch and die and means for feeding ears on the heads comprising a hopper for ears, a primary ear-feeding device engaging the holes in the ears, a secondary ear-feeding device engaging the edges of the ears, and connections from the punch and die for operating the primary and secondary feeding devices simultaneously in opposite directions.
- 60 12. In a head press, means for providing ears on bosses comprising a punch and die and means for feeding ears on the heads comprising a hopper for ears, a primary ear-feeding device engaging the holes in the ears, a secondary ear-feeding device engaging the edges of the ears, and connections from the punch and die for operating the primary and secondary feeding devices simultaneously in opposite directions, said connections being adapted to operate the primary feeding device rearwardly and the secondary feeding device forwardly before the die and punch are together.
- 65 13. In a head press, means for providing ears on bosses comprising a punch and die and means for feeding ears on the heads comprising a hopper for ears, a primary ear-feeding device engaging the holes in the ears, a secondary ear-feeding device engaging the edges of the ears, and connections from the punch and die for operating the primary and secondary feeding devices simultaneously in opposite directions, said connections being adapted to operate the primary feeding device rearwardly and the secondary feeding device forwardly before the die and punch are together and to operate the feeding devices in the opposite direction thereafter.
- 70 14. In a head press, means for feeding heads, devices for making bung-holes and producing bosses thereon, means for providing ears on bosses comprising a punch and die and means for feeding ears on the heads comprising a hopper for ears, a primary ear-feeding device and a secondary ear-feeding device.
- 75 15. In a head press, means for feeding

heads, devices for making bung-holes and producing bosses thereon, means for providing ears on bosses comprising a punch and die and means for feeding ears on the 5 heads comprising a hopper for ears, a primary ear-feeding device, a secondary ear-feeding device, and connections from the punch and die for operating the primary and secondary feeding devices simultaneously in opposite directions.

16. In a head press, means for feeding heads, devices for making bung-holes and producing bosses thereon, means for providing ears on bosses comprising a punch and die and means for feeding ears on the heads comprising a hopper for ears, a primary ear-feeding device, a secondary ear-feeding device, and connections from the punch and die for operating the primary and secondary 15 feeding devices simultaneously in opposite directions, said connections being adapted to operate the primary feeding device rearwardly and the secondary feeding device forwardly before the die and punch are together.

17. In a head press, means for feeding heads, devices for making bung-holes and producing bosses thereon, means for providing ears on bosses comprising a punch and 30 die and means for feeding ears on the heads comprising a hopper for ears, a primary ear-feeding device, a secondary ear-feeding device, and connections from the punch and die for operating the primary and secondary feeding devices simultaneously in opposite directions, said connections being adapted to operate the primary feeding device rearwardly and the secondary feeding device forwardly before the die and punch are together and to operate the feeding devices in the opposite direction thereafter.

18. In a head press, means for feeding heads, devices for making bung-holes and producing bosses thereon, means for providing ears on bosses comprising a punch and die and means for feeding ears on the heads comprising a hopper for ears, a primary ear-feeding device engaging the holes in the 45 ears and a secondary ear-feeding device engaging the edges of the ears.

19. In a head press, means for feeding heads, devices for making bung-holes and producing bosses thereon, means for providing 50 ears on bosses comprising a punch and die and means for feeding ears on the heads comprising a hopper for ears, a primary ear-feeding device engaging the holes in the ears, a secondary ear-feeding device engaging the edges of the ears, and connections from the punch and die for operating the primary and secondary feeding devices simultaneously in opposite directions.

20. In a head press, means for feeding heads, devices for making bung-holes and

producing bosses thereon, means for providing ears on bosses comprising a punch and die and means for feeding ears on the heads comprising a hopper for ears, a primary ear-feeding device engaging the holes in the ears, a secondary ear-feeding device engaging the edges of the ears and connections from the punch and die for operating the primary and secondary feeding devices simultaneously in opposite directions, said 70 connections being adapted to operate the primary feeding device rearwardly and the secondary feeding device forwardly before the die and punch are together.

21. In a head press, means for feeding heads, devices for making bung-holes and producing bosses thereon, means for providing ears on bosses comprising a punch and die and means for feeding ears on the heads comprising a hopper for ears, a primary ear-feeding device engaging the holes in the ears, a secondary ear-feeding device engaging the edges of the ears and connections from the punch and die for operating the primary and secondary feeding devices 80 simultaneously in opposite directions, said connections being adapted to operate the primary feeding device rearwardly and the secondary feeding device forwardly before the die and punch are together and to operate the feeding devices in the opposite direction thereafter.

22. In a head press, means for providing ears on bosses comprising a punch and die and means for feeding ears on the heads comprising a hopper for ears, a primary ear-feeding device, a secondary ear-feeding device, and a device for holding the ear while being transferred from the primary to the secondary feeding device.

23. In a head press, means for providing ears on bosses comprising a punch and die and means for feeding ears on the heads comprising a hopper for ears, a primary ear-feeding device engaging the holes in the 100 ears, a secondary ear-feeding device engaging the edges of the ears, and a device for holding the ear while being transferred from the primary to the secondary feeding device.

24. In a head press, means for feeding heads, devices for making bung-holes and producing bosses thereon, means for providing ears on bosses comprising a punch and die and means for feeding ears on the heads comprising a hopper for ears, a primary ear-feeding device, a secondary ear-feeding device, and a device for holding the ear while being transferred from the primary to the secondary feeding device.

25. In a head press, means for feeding heads, devices for making bung-holes and producing bosses thereon, means for providing ears on bosses comprising a punch and die and means for feeding ears on the heads

115

130

6
 comprising a hopper for ears, a primary ear-feeding device engaging the holes in the ears, a secondary ear-feeding device engaging the edges of the ears, and a device for holding the ear while being transferred from the primary to the secondary feeding device.

26. In a head press, means for providing ears on bosses comprising a punch and die and means for feeding ears on the heads comprising a hopper for ears, a primary ear-feeding device, a secondary ear-feeding device, and a spring clip engaging the upturned end of the ear for holding the ear while being transferred from the primary to the secondary feeding device.

27. In a head press, means for providing ears on bosses comprising a punch and die and means for feeding ears on the heads comprising a hopper for ears, a primary ear-feeding device engaging the holes in the ears, a secondary ear-feeding device engaging the edges of the ears, and a spring clip engaging the upturned end of the ear for holding the ear while being transferred from the primary to the secondary feeding device.

28. In a head press, means for feeding heads, devices for making bung-holes and producing bosses thereon, means for providing ears on bosses comprising a punch and die and means for feeding ears on the heads comprising a hopper for ears, a primary ear-feeding device, a secondary ear-feeding device, and a spring clip engaging the upturned end of the ear for holding the ear while being transferred from the primary to the secondary feeding device.

ear while being transferred from the primary to the secondary feeding device. 35

29. In a head press, means for feeding heads, devices for making bung-holes and producing bosses thereon, means for providing ears on bosses comprising a punch and die and means for feeding ears on the heads comprising a hopper for ears, a primary ear-feeding device engaging the holes in the ears, a secondary ear-feeding device engaging the edges of the ears, and a spring clip 40 engaging the upturned end of the ear for holding the ear while being transferred from the primary to the secondary feeding device. 45

30. In a press, means for feeding heads, devices for making bung-holes and producing bosses thereon, devices for fastening ears on the bosses, and a sliding carriage on which the moving parts of both said devices are carried. 50

31. In a press, means for feeding heads, 55 adjustably mounted devices for making bung-holes and producing bosses thereon, adjustably mounted devices for fastening ears on the bosses, and a sliding carriage on which the moving parts of both said devices 60 are carried.

In testimony that I claim the foregoing I have hereunto set my hand.

FLOYD D. STOWE.
